GLOVE ORNAMENT

John A. Mitchell, Providence, R. I.

Application November 10, 1932, Serial No. 642,076

10 Claims. (Cl. 41—34)

My invention relates to improvements in glove ornaments and includes an ornamental member preferably in simulation of a ring, preferably comprising a ring top adapted to be secured on top of a glove finger to give the imitation of a ring on the outside of the glove.

So far as I am aware I am the first to provide any type of ornament for a glove finger or to devise any type of means for securing an ornament to a glove finger. While I preferably employ a ring top it is obvious that any other type of an ornament may be applied.

The desire of human beings to cover themselves with ornaments has existed ever since the beginning of civilization or even the human race. Civilization and society also decree that gloves be worn even when they are not needed for the purpose of warmth. In all the years that gloves have been worn the fingers thereof have been bare and it has been generally thought that the one place where ladies and gentlemen could not adorn themselves was on their gloves.

An object of my invention is to provide an ornamentation and means whereby the glove may be suitably ornamented and thus satisfy this craving of the human race for self adornment.

A further object of my invention is to provide an ornament for the finger which may be readily taken on and off if desired with the glove.

A further feature of my invention is to provide a glove ornament which may be sold directly in the box with the gloves and thereby tend to increase the sale of gloves with their attendant cleanly and warmth-giving results.

These and such other objects of my invention as may hereinafter appear will be best understood from a description of the accompanying drawing which illustrates various embodiments thereof.

In the drawing, Fig. 1 is a plan view of a pair of gloves packed for sale having my improved ornament attached to a finger thereof.

Fig. 2 is a cross sectional view taken through the glove finger and attached ring top.

Fig. 3 is a longitudinal sectional view taken along the line 3—3 of Fig. 2.

Fig. 4 is a reverse plan view of the ring top I preferably employ.

Fig. 5 is a plan view of the attaching strip and female fastener element I employ to detachably secure the ring top to the glove finger.

Fig. 6 is a longitudinal sectional view illustrating a modified form of my invention in which

the female fastener element is secured to the glove finger itself.

Fig. 7 is a plan view of the female fastener element directly secured to a glove finger.

Fig. 8 is a reverse plan view of the underneath portion of the glove finger showing the means I employ to secure the female fastener element of this embodiment of my invention thereto.

Fig. 9 is a longitudinal sectional view taken through a ring top showing a different embodiment of my invention employing a female separable fastener element in the ring top and a male separable fastener element on the glove finger.

Fig. 10 is a plan view of the male fastener element of the embodiment shown in Fig. 9.

Fig. 11 is a perspective view of the female fastener element which is secured to the ring top edges of the embodiment shown in Fig. 9.

Fig. 12 is a longitudinal sectional view illustrating a plurality of well known separable glove fastener elements which may be employed to detachably secure a ring top or other ornament to a glove finger of a slightly different form from that shown in Figs. 9—11.

In the drawing, 10 generally illustrates a standard type of glove to which my invention may be attached.

As shown in Fig. 1 for purposes of sale the glove may be packed in the usual packing box 12 in the flat shape shown and my improved ornament 14 may be secured directly to a finger of the glove. Aside from helping to satisfy the craving of human beings to adorn themselves by making it possible for individuals to adorn their gloves, my invention also provides a ready sales argument for the gloves to which it may be attached, as it provides a novel type of attractive display for the gloves particularly when packed in the package.

As stated, my invention comprises a glove having fingers 18, a ring top 14, or other ornament and means 16 to secure preferably detachably said ring top or other ornament to the glove finger 18.

While any type of ornament may be employed, I preferably employ a standard ring top, which as shown includes the setting 20 and the stone 22. The setting 20 preferably has side walls 24 which bend down over the sides of the glove finger. I have shown in the drawing various types of embodiments of means to preferably detachably secure the ring top or other ornament to the glove finger, which cover various types of separable fasteners which may, if desired, be made so as not to be separable. A separable fastener usu-

ally includes a pointed male member which is adapted to slide or slip into and be retained in position by a female member. In the embodiments shown the male member 26 may be attached to the ring top and the female member 28 may be attached to the glove or vice versa. In the embodiments shown in Figs. 2-5, there is provided a metal strip 30 adapted to extend underneath the ring top and transversely over the glove finger. In this embodiment the male fastener element 26 is substantially flat and is provided with slots 34 for receiving the metal strip 30 therein to firmly secure the male separable fastener element to the under surface of the ring top supplemented by solder if desired. While the other separable fastener element may, if desired, be directly attached to the glove as in the embodiment shown in Figs. 6, 7 and 8, I preferably attach it to a narrow, leather, cloth 20 or other strip 36. If desired the strip 36 may be constructed of the same material as the glove. The narrow strip 36 extends across the glove finger at a point at which it is desired to detachably secure the ornament thereto and preferably has the ends 38 thereof secured to the glove by 25 the same stitchings 40 that secure the sides 42 of the fingers to the tops 44 thereof. In the embodiment shown in Figs. 1-4 the female separable fastener element is secured at right angles 30 across the strip 36, preferably through the slots 49 therein and is provided with the upwardly projecting side walls 47, end walls 48 and 50 and the top walls 52 near one end thereof projecting for at least a portion of the distance 35 thereover. The end wall 50 is preferably tilted obliquely forward to be of lesser height than the end wall 48 for easy insertion of the walls 32 of the male member 26 underneath the top walls 52 of the female member 28. It is obvious that 40 to attach the ornament to the glove finger, it is merely necessary to align the side edges 32 of the male element within the top walls 52 of the female element and slide the male element "home" until one end thereof abuts the end wall 48 and the other end thereof sinks within the female member to abut the opposite end wall 50 thereof, the preferably tapered edges 32 merely sliding and being retained in position underneath the top walls 52 of the female separable fastener element. If desired after insertion the end wall 50 may be bent over the end of the male fastener element to firmly secure the male fastener element within the female. In case they are 45 not bent over however, it is obvious that one end of the male member may be pushed up above the wall 50 and male member laterally withdrawn from the retaining sheath formed by the top walls 52 of the female member. As shown in Figs. 6-8, the female member 28 may be attached 50 directly to a glove finger, eliminating the necessity for the strip 36. In this instance the female element 28 is provided with the prong holes 54. A plate 56 is provided preferably arcuately concaved to fit over the top of the finger and is 55 provided with the prongs 58 which project upwardly therefrom through the glove finger 18 and into the prong holes 54 where they may have the heads thereof upset as at 60. It is thus obvious that in this embodiment, the female element is secured to the glove itself directly by means of the plate 56, the construction of the male member and its functioning being similar to that of the embodiment shown in Figs. 1-5. As shown in Figs. 9-11 a construction similar to a separable glove fastener means may if

desired be employed, in this instance attaching the male member thereof to the glove finger 18 and the female member to the ring top. In this instance the female member merely comprises the strip 30 provided with the two holes 62, preferably of cross formation to provide the resilient points 64 for receiving the head 66 of the male member therebetween. The points 64 will resiliently give to permit the entrance of the enlarged head 66 of the male member therein. The male member 26 has the male portion, including the heads 66 of general pear shape and is provided with the slits 68 through which the stitching 70 may directly attach the male element 26 to either the glove finger 18 or the strip 36. The embodiment shown in Figs. 9-11 is a simplified type of standard separable glove fastener means, although if desired as shown in Fig. 12 a pair of usual glove fasteners 72 may be provided and the male portions thereof secured in any suitable fashion, such as by the stitching 70 to the glove finger 18 or cross strip 36 and the female elements 28 mounted on the strip 30.

It is thus apparent that I have provided a 100 novel type of ornamentation for gloves, which applies a means for ornamenting gloves hitherto unknown and which provides an attractive ornament not only when worn, but also when the gloves are on display.

It is understood that my invention is not limited to the specific embodiments shown and that various deviations may be made therefrom without departing from the spirit and scope of the appended claims.

What I claim is:

1. In combination with a glove having fingers, a ring top and means to detachably secure said ring top to a glove finger.
2. In combination with a glove having fingers, a ring top and means to secure said ring top to a glove finger.
3. In combination, a glove finger, a ring top adapted to overlie said finger having side walls adapted to overlie the sides of said finger, and means to detachably secure said ring top to said finger, including a male fastener part projecting from one of said members and a complementary female fastener part on the other of said members.
4. In combination, a glove finger, a strip extending across said finger and secured to said finger by the usual glove top glove side stitching, a ring top, and fastener elements secured to said ring top and strip including a male member projecting from one of said members and a complementary female member projecting from the other of said members.
5. A glove ornament, comprising a ring top, and fastener means to secure said glove ornament to a glove finger, comprising a metal strip secured across the under side of said ring top over and across said finger, a slidably flat male fastener element secured at right angles to the lower edge of said metal strip and having the sides thereof downwardly tapered near the edges thereof, a flat female separable fastener element securable to said finger parallel thereto having upwardly projecting end walls, and top walls near one end thereof, whereby when said male element is slid laterally under the top walls thereof it may fit between the end walls thereof and be retained to said finger by said top walls of said female element.
6. A glove ornament, comprising a ring top and

- fastener means to secure said glove ornament to a glove finger, comprising a metal strip secured across the under side of said ring top over and across said finger, a slideable flat fastener element 5 secured at right angles across the lower edge of said strip and a separable fastener element securable to said finger parallel thereto for receiving said flat fastener element to detachably secure said ring top to said glove finger.
- 10 7. Fastener means to secure one element to another, comprising a metal strip secured across the under side of one element, a slideable flat male fastener element secured at right angles to the lower edge of said metal strip and having the 15 sides thereof downwardly tapered near the edges thereof, a flat female fastener element secured to said other element having upwardly projecting end walls, and top walls near one end thereof, constructed so that when said male element is 20 slid laterally under the top walls thereof it may fit between the end walls thereof and be retained to said first element by said top walls of said female element.
8. Fastener means to secure one element to another, comprising a metal strip secured across the under side of one element top over and across said finger top over and across said finger, a slideable flat male fastener element secured at right 25 angles to the lower edge of said metal strip and having the sides thereof downwardly tapered near the edges thereof, a flat female separable fastener element secured to the other element 30 having the sides thereof downwardly tapered near the edges thereof, a flat female separable fastener element secured to the other element
- having upwardly projecting end walls, and top walls near one end thereof, constructed so that when said male element is slid laterally under the top walls thereof it may fit between the end walls thereof and be retained to said first element by said top walls of said female element.
9. Fastener means to secure one element to another, comprising a slideable flat male fastener element secured to one element and having the sides thereof downwardly tapered near the edges thereof, a flat female fastener element secured to said other element having upwardly projecting end walls, and top walls near one end thereof, constructed so that when said male element is slid laterally under the top walls thereof it may fit between the end walls thereof and be retained to said first element by said top walls of said female element.
10. Fastener means to secure one element to another, comprising a slideable flat male fastener element secured to one element and having the sides thereof downwardly tapered near the edges thereof, a flat female separable fastener element secured to the other element having upwardly projecting end walls, and top walls near one end thereof, constructed so that when said male element is slid laterally under the top walls thereof it may fit between the end walls thereof and be retained to said first element by said top walls of said female element.

CERTIFICATE OF CORRECTION.

Patent No. 1,949,755.

March 6, 1934.

JOHN A. MITCHELL.

It is hereby certified that error appears in the printed specification of the above numbered patent requiring correction as follows: Page 3, lines 26 and 27, claim 8, strike out the words "top over and across said finger top over and across said finger; and that the said Letters Patent should be read with this correction therein that the same may conform to the record of the case in the Patent Office.

Signed and sealed this 15th day of May, A. D. 1934.

Bryan M. Battey
